UNITED STATES PATENT OFFICE.

HUGH CHRISTIE, OF BOSTON, ASSIGNOR TO THE BIGELOW CARPET COMPANY, OF CLINTON, MASSACHUSETTS.

DESIGN FOR A CARPET.

SPECIFICATION forming part of Design No. 12,455, dated September 13, 1881.

Application filed August 1, 1881. Term of patent 3½ years.

To all whom it may concern:

Be it known that I, HUGH CHRISTIE, of Boston, in the county of Suffolk and State of Massachusetts, have invented a new and original 5 Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The group D is composed of a rose-like figure, H, surrounded by curving leaves, and of 15 the figure f, consisting of slender sprays, with leaves and flowers thereon, projecting from it. The group D also contains the figure G, consisting of a pair of ornamented vases, from one of which projects the figure e, consisting of leafy 20 sprays and twigs. These vases G appear to rest upon a pedestal, K, made up of various segments resembling bricks. From one side of this pedestal K projects the figure a, consisting of a bunch of leaves, from which hang 25 moss-like projections extending over the stem of the figure g, also projecting from K, which bears on its end leaves and flowers, and from the other side of the figure K projects the figure i, a branch with leaves and flowers thereon.

30 The figure k, projecting from the figure H, consists of a bunch of circular leaves, from which projects over into the figure f a flower set on a slender stem.

The figure c also projects from the figure H, 35 and consists of a leafy branch extending toward the figure i.

The group E contains the figure p, resembling a section of a rustic fence, having projecting from one end thereof the figure r, a rose with 40 surrounding leaves, and from the other end the

figure h, a vine with leaves, flowers, and circular berries thereon.

The figure q of the group E is a rectangular figure resembling lattice-work, having projecting from one side the mossy tuft t, and from its 45 other side the figure j, a rose-like figure with surrounding leaves, from which project slender leafy sprays and a bunch of circular flowers.

The figure d consists of a rustic lattice-work or fence, over which grow leaves, flowers, and 50 mossy tufts.

The figure s is a branch bearing upon it a rose, with leafy branches and mossy sprays projecting around it.

The figure b resembles a rustic fence or lattice, from one corner of which projects the circular bunch of flowers o, with a leafy branch extending therefrom. The bunch o connects the figures r and s, as shown.

I claim—

1. The design for carpets, consisting of the group D, containing figures K, i; a, g, G, c, e, k, H, and f, substantially as shown.

2. The design for carpets, consisting of the group E, containing figures j, q, t, h, p, and r, 65 substantially as shown.

3. The design for carpets, consisting of the figures b, o, d, and s, substantially as shown.

4. The design for carpets, consisting of the figure d, substantially as shown.

5. The design for carpets, consisting of the group D, containing figures H k f e G c a g K i, group E, containing figures j, q, t, h, p, and r, and figures b, o, s, and d, substantially as shown.

HUGH CHRISTIE.
